UNITED STATES PATENT OFFICE.

CHARLES H. BOARDMAN, OF VIVIAN, WEST VIRGINIA, ASSIGNOR TO SUNDRIES MANUFACTURING COMPANY, OF PORTLAND, MAINE, A CORPORATION OF MAINE.

MINING-MACHINE.

1,199,757.

Specification of Letters Patent.

Patented Oct. 3, 1916.

Application filed February 5, 1915. Serial No. 6,326.

To all whom it may concern:

Be it known that I, CHARLES H. BOARDMAN, a citizen of the United States, residing at Vivian, in the county of McDowell and 5 State of West Virginia, have invented certain new and useful Improvements in Mining-Machines, of which the following is a specification.

This invention is a machine of the type 10 which acts to undercut the mineral at the end of a heading, or any other wall of a passage or chamber in a mine, being particularly designed for coal mining, although not limited in this respect.

15 Attempts have heretofore been made to utilize machines which have only a single cutting mechanism, so located with respect to the frame of the machine that when the latter is placed on the floor of a mine, and 20 brought up to the wall from which the mineral is to be cut, a narrow slit extending horizontally into the wall near the floor will be made. Such machines are unsatisfactory in their operation, because the slits produced 25 are usually so shallow that when the superposed mineral is broken down by wedging or blasting, the mineral is not broken into sufficiently small lumps for convenient and practical loading and handling, except by 30 employment of an excessively large charge of explosive, but is loosened as a large mass of, perhaps, several tons in weight, which must be subsequently shot or picked to pieces. Another method of obtaining pieces 35 of convenient size by employing a shallow undercut, is by making a heavy blast and breaking the mass of coal by the force of the blast. This, however, is wasteful of explosive, and has the additional disadvantage of 40 shattering the coal too much, with production of too large a proportion of dust.

45 My invention aims to overcome the objections above indicated, by providing a simply constructed and easily operated machine for making a deep undercut, by means of spaced apart cutting mechanisms located one above the other, with a clear space between them, to the end that the machine may make two separated cuts simultaneously, and at the 50 same time remove the mineral between the cuts. The upper cutting mechanism is arranged to cut into the mineral wall to a greater depth than the lower cutting mechanism, whereby, when the cutting action has

been completed, a deep undercut is produced 55 having a well defined overhang. Thus a considerable distance is provided through which the mineral above the undercut may fall with a full rolling motion, as it is supported at the back and unsupported at the 60 front, and when said mineral is brought down by any of the commonly practised methods, this motion causes it to break into sufficiently small lumps, and out into the room, so that it may be conveniently 65 handled.

A further object is to provide means for weakening the strata of the coal being operated upon by the cutting mechanisms, whereby the mass is caused to drop and be 70 conveniently removed by the cutting mechanisms in their operation.

The invention will be hereinafter fully set forth and particularly pointed out in the claims.

75 In the accompanying drawings:—Figure 1 is a side elevation illustrating my invention, the mineral wall being shown in section, the frame of the machine and the power mechanism being conventionally 80 shown. Fig. 2 is a plan view. Fig. 3 represents a section of the mine wall, illustrating the character of the work performed by the machine. Figs. 4 and 5 are detail views illustrating the supplemental cutter located 85 between the cutting mechanisms.

90 Referring to the drawings, 10 designates the frame of the machine, of any suitable or preferred construction, which contains in its interior the power mechanism and connections for operating the parts, and from which extend two arms 11, 12, one directly above the other. The arm 11 is longer than the arm 12, the arrangement being such that the forward end of the upper arm extends beyond the forward end of the lower arm. Both arms are constructed with guide-ways at their edges, and guide wheels or pulleys, through and about which pass endless chains 14, 15, respectively, carrying 100 cutters or bits 16. Where the chains pass into the frame or casing 10, they are supported and driven by suitable drive wheels or sprockets (not shown). By the foregoing arrangement the working extremity of 105 the upper chain extends beyond the working extremity of the lower chain. As appears from the side view (Fig. 1), certain of the

cutters are off-set respectively upwardly and downwardly from the carrying chain to a distance somewhat above and below the supporting arm, while other cutters extend straight out from the chain. This arrangement is for the purpose of enabling the slot cut, to be somewhat wider than the arm, and to afford sufficient clearance for the same.

10 Interposed between the arms 11 and 12, and mounted upon a horizontal axis is a star-shaped cutter 17, the shaft of which is mounted in bearings carried by a rotatable ring 18. The cutter 17 is supported by the 15 upper arm 11 at a point directly above the cutting extremity of the lower chain.

At the rear of the machine are lugs 20, 21, between which are guide pulleys 22 and operating wheels for the chains or cables 20 which are usually used for securing the machine, or for moving it. At the sides of the frame are pulleys 23 and hooks 24 for the same purpose. Power is supplied in any suitable manner, a cable 25 being illustrated 25 for transmitting electrical energy, which energy may be converted into mechanical power by an electric motor.

The internal construction of the machine, and the driving motor inclosed in the frame 30 or casing 10, have not been illustrated, for the reason that such construction and motor form no part of my present invention, and it is sufficient for the purposes of the invention, that the cutter carrying chains are 35 driven by any suitable form of motor and transmission mechanism.

In operation, the machine is brought up to the wall to be attacked, at one end or side of the passage or room 26, and is fed forward into the wall as fast as the cutters remove the mineral. As the cutters advance, the points of the cutter 17 project in the direction of travel, said cutter being so located that it will be engaged in the solid 45 coal between the upper and lower cutters, and not touch the upper side of the kerf, thus compelling it to dig or gouge chunks out of the solid intervening block. This necessarily weakens the strata of coal, and 50 the bits in the chains, working so close to it, will compel the whole mass to drop and be taken out by the action of the chains. As the cutters advance, the mineral between the arms 11 and 12 falls by its own weight and 55 disintegrates, breaking up into pieces small enough to be removed by the chains. When the cutter carrying arms have been advanced as far as practicable, the machine as a whole is moved sidewise across the wall, as far as 60 desired, whereby a slot parallel with the floor, having the desired extent, is produced. This slot or kerf is shown in cross section, both in Figs. 1 and 3. The mineral between the cutter being thin, or narrow, and weakened by the cutter 17, sags down and is

broken and dragged out in pieces of sizes known as "egg" and "lump" sizes or grades, the removal of the broken pieces being effected by the upper and lower cutters and chains, which travel in the same direction. 70

Thus all the mineral between the uppermost and lowermost cutters is removed, whereupon a single, wide undercut is left, provided with the overhang 26^a. The material in the wall above this wide undercut may 75

then be broken down by any of the commonly used methods, and in a way such as to produce the desired size, the height of the undercut being such that the overhanging mass, in falling to the bottom of the cut, 80

fulcrums on the overhanging portion and strikes the bottom with sufficient force to be broken into lumps not too large to be conveniently loaded by the miners into mine cars, without requiring a blast heavy enough 85

to crush the coal by the force of the blast alone, and without causing the coal to be so much crushed as to be pulverized to any great extent. No power is applied to the 90

cutter, other than the motion of the machine as it moves, the path followed by the cutter 17 being indicated in Fig. 6. In operation, 95

the points of the cutter 17 that extend above the axle of the cutter, do not touch any coal, but the points below the axle engage the 95

broken down coal between the chain cutters. When the machine is propelled in any one direction, the depending points of the cutter being in contact with the top of the broken 100

down coal, the cutter is caused to revolve, and as it comes in contact with the top of 105

the coal it necessarily digs itself down into the same. When the machine is made to cut in a direct right angle to the direction of travel at any one time, the fact that but 110

two of the cutting points of the cutter 17 can be engaged in cutting coal at one time, causes one of the points to be deeper into the coal than the other, and consequently, when 115

the machine is turned, the point of the cutter that is deeper in the coal than the other one, will not be moved as quickly as the one that is not so firmly embedded, and therefore the line in which the axle of the cutter 17 revolves, must turn so as to push the star in 120

position to run in the same direction as the machine will then be going. In other words, the instant that the point of the star cutter gives in the least, the whole horizontal bearing ring 18 will immediately turn so as to 125

allow the cutter 17 to work in the direction required. As the machine penetrates the wall of coal the cutter 17 follows the path indicated at 26 until the machine has entered to the desired depth. When the machine 130

starts its lateral movement, the ring 18 is caused to make a quarter turn, whereupon the cutter 17 follows the path indicated at 27. When the lateral cut is completed, and the machine is to be withdrawn, 130

the bearing ring 18 is again turned a quarter turn, causing the cutter 17 to follow the path indicated at 28.

The above described machine is specially 5 adapted for use in mining soft coal, although it is not limited to this particular kind of coal. Its particular advantage lies in the fact that the kerf or slot formed by it is very similar in form and style to that made 10 by the miner when using hand tools. It thus has all of the advantages of hand mining, in that the coal instead of coming straight down, is caused to come down with a rolling or forward motion, because of the 15 fulcrum formed at the back of the kerf, is removed in moderately large lumps, with the production of a minimum proportion of dust or finely granulated coal. It also possesses the additional advantage that the coal 20 may be rapidly and economically mined.

Having thus explained the nature of my invention and described an operative manner of constructing and using the same, although without attempting to set forth all 25 of the forms in which it may be made, or all of the forms of its use, what I claim is:—

1. A mining machine of the character described comprising a frame, spaced apart endless chains carried by said frame and arranged one above the other, the forward 30 working extremity of the upper chain extending beyond the forward working extremity of the other chain, and cutters carried by said chains for cutting the material and removing the severed material as the cutting 35 progresses.

2. A mining machine of the character de-

scribed comprising a frame, spaced apart endless chains carried by said frame and arranged one above the other, cutters carried 40 by said chains for cutting the material and removing the severed material as the cutting progresses, and a cutting wheel mounted between said chains and acting at right angles to the cutting action of said chains. 45

3. A mining machine of the character described comprising a frame, spaced apart endless chains carried by said frame, the forward working extremity of one chain extending beyond the forward working extremity of the other chain, cutters carried 50 by said chains for cutting the material and removing the severed material as the cutting progresses, and a cutting wheel mounted on a horizontal axis between said chains and having its cutting portion extending beyond the working extremity of the shorter chain. 55

4. A mining machine of the character described comprising a frame, spaced apart endless chains carried by said frame and arranged one above the other, cutters carried 60 by said chains for cutting the material and removing the severed material as the cutting progresses, a cutting wheel mounted between the chains and rotatable on a horizontal axis, and a support for said cutter rotatable upon 65 a vertical axis.

In testimony whereof I have affixed my signature, in presence of two witnesses.

CHARLES H. BOARDMAN.
